UNITED STATES PATENT OFFICE.

HENRY WARD HOWELL, OF BUTTE, MONTANA.

BUILDING WALL.

1,421,007.

Specification of Letters Patent. Patented June 27, 1922.

Application filed January 26, 1921. Serial No. 439,988.

To all whom it may concern:

Be it known that I, HENRY WARD HOWELL, a citizen of the United States, and a resident of Butte, in the county of Silver Bow 5 and State of Montana, have invented certain new and useful Improvements in Building Walls, of which the following is a specification.

My invention relates to concrete wall 10 structures for buildings, and the purpose of my invention is the provision of a building wall comprised of standard units of various sizes which are formed and can be associated with each other so as to provide walls of 15 any desired thickness while employing substantially the same amount of labor and material. Furthermore my invention provides novel means for securing the building units in wall formation and against movement one with relation to the other whereby 20 a building wall of an extremely simple, durable and efficient construction is formed.

I will describe one form of building unit and two forms of building walls, each embodying my invention, and will then point 25 out the novel features thereof in claims.

In the accompanying drawings:

Figure 1 is a view showing in perspective one form of building unit embodying my invention.

Figure 2 is a vertical sectional view of a building wall constructed in accordance with my invention and in which is employed the building units shown in Figure 1.

Figure 3 is a plan showing the channel for the concrete beam hereinafter described.

Figure 4 is an enlarged detail sectional view of the spacing strip employed in the wall shown in Figures 2 and 3.

Figures 5 and 6 are views similar to Figure 4 showing modified forms of spacing strips.

Figure 7 is a horizontal section through the wall taken on the line 7—7 of Figure 2.

Figure 8 is a fragmentary vertical sectional view of a building wall embodying my invention showing a method of temporarily securing the building units in their proper relative position pending the casting 40 of the concrete beam hereinafter described.

Similar reference characters refer to similar parts in each of the several views.

Referring now to the drawings, my invention in its present embodiment consists 55 in the main of a plurality of units or slabs

S of the same length and thickness but of varying widths, each of which, as shown in Figure 1, comprises a flat panel 15 of rectangular form formed along its lower edge with a bottom flange 16 connected at its ends to the lower ends of side flanges 17. The upper ends of the side flanges 17 are connected by a top flange 18, it being noted that the side flanges terminate rearwardly of the upper end of the panel 15 with the flange 18 occupying a corresponding position. This portion of the panel 15 projecting above the top flange 18 is relatively thick and constitutes a channel forming lip designated at 60 15^a, as will be hereinafter described. The longitudinal edges of the panel 15 are formed with grooves 15^b in Figure 1 coextensive in length with the panel and which are designed to coact with the grooves of an adjacent slab to provide channels adapted for the reception of plaster to effect an interlocking of any two adjacent slabs against relative lateral movement, and to provide an 65 air and weather tight joint.

Each unit S is formed of concrete which is reinforced in any suitable manner, the side flanges 17 being further reinforced by imbedding rods R arranged in the manner shown in Figure 1 so that their opposite 70 ends project above and below the top and bottom flanges, respectively.

Referring now to Figures 2 and 3, I have here shown one form of building wall embodying my invention which is constructed 75 in the main of the building units just described. As here shown, the building wall contains an upper story and a lower story, the latter being made up of a plurality of units S which are embedded at their lower 80 ends in a concrete base designated at B. The units S are arranged in confronting relation to each other so that their flanges 16, 17 and 18 are interposed between the panels 15 of any two confronting units. As 85 shown in Figures 3 and 7, the building units formed on the inner and outer sides of the wall are arranged side by side or edge to edge with the units of the inner side being arranged in staggered relation with the units 90 of the outer side as shown in Figure 3, or in registering relation as shown in Figure 7. Either method may be employed in constructing the building wall I having shown the two methods to demonstrate the flexibility of the system. The staggered arrangement 95 is perhaps preferable because of the 100 105 110

disalignement of the joint between adjacent units. Other advantages of this form will become apparent as the description proceeds.

- 5 As previously described, the building units comprising the lower story of the wall are in part secured in vertical position by partially embedding them in the concrete base B. As a further securing means, the 10 lower projecting ends of the rods R likewise may extend into the base B. The building units constituting the inner side of the wall are maintained in definite spaced relation to the units comprising the outer sides of 15 the wall and in alinement with each other by means of spacing strips T and T' arranged between the confronting edges of the flanges 16 and 18, as clearly shown in Figure 2. These spacing strips are preferably 20 formed of wood, the spacing strip T reposing on the base B and thus serving to prevent any inward movement of the lower ends of the units. The upper ends of the units are maintained in alinement and in 25 definite spaced relation to each other by the spacing strip T' which is supported in position between the flanges 18 by a metallic plate or strip 19 which is secured to the upper side of the spacing strip and is of a 30 width exceeding that of the strip so as to provide flanges which rest on the upper sides of the flanges 18 and thus support the spacing strip in proper spacing position. In Figure 4, a detail transverse sectional view 35 of the spacing strip T' is shown, while in Figure 5, a modified form of spacing strip T² is shown. In this latter form the strip is constructed of metal bent to provide an intermediate portion 19^a that is supported 40 in spacing position between the flanges 18 by flanges 19^b formed on the opposite edges of such intermediate portion. In Figure 6, a detail sectional view of the spacing strip T is shown.
- 45 With the building units S of the lower story maintained in proper spaced relation by the spacing strips, a channel coextensive in length with the wall is formed at the upper end of the units and between the lips 50 15^a. This channel is shaped for the reception of concrete, which, when hardened, is adapted to effectively secure the units of the inner side of the wall to the units of the outer side of the wall, and to maintain 55 all in permanent alinement, and at the same time to form a base upon which the second story of the wall is adapted to be formed. In this manner a monolithic beam may be cast around an entire building.
- 60 The thickness of the wall may be varied by varying the width of the spacing strips. In this way, as shown in Figure 2, a shelf A may be provided at the top of any story of a building to support the floor of the next 65 upper story.

To maintain the building units in wall formation pending the casting of the concrete beam, the upper ends of the rods R may be attached to the spacing strip by wires or other metallic ties, as shown in Figure 8, or may be rigidly connected to each other by binding wires 20 and a connecting rod 21. It is conceivable that there may be still other ways of binding the building units together either directly or by being tied on both sides to the spacing strip. In this manner the several building units are held in firm engagement with the spacing strip T' so that the introduction of the concrete into the channel can be carried out without fear of disturbing the arrangement of the building units. This application of the concrete to the channel obviously embeds the upper ends of the rod R, the wire 20, and the rod 21 within this concrete so that when the latter is set, those elements provide reinforcing means which prevent disintegration of the body of concrete.

As shown in Figures 3 and 7, any two adjacent building units are rigidly connected at their contacting edges against lateral movement by means of plaster or cement grout indicated at 22 which is introduced into the channels formed by the grooves 15^b so formed as to provide dove-tailed channels.

As shown in Figure 2, the second story of the building wall is relatively narrow as compared with the first story, this reduction in width allowing for the supporting of the upper floor as has been described. The second story is made up of building units S having the same structural details as the building units comprised in the first story. The spacing of the units comprised in the inner side of the wall from the units comprised in the outer side of the wall is necessarily less, and to this end relatively narrower spacing strips T² and T³ are provided. The lips 15^a of the units of the upper story likewise form a channel in which concrete may be deposited for forming a base adapted for the support of another story or the roof structure.

It should be understood that the elements herein referred to as being made of concrete may be made of any like plastic material.

From the preceding description it will be manifest that I have provided a building wall made up of a plurality of building units of standard sizes, and varying only in width, and providing an inexpensive form of concrete wall construction with the elimination of wooden or metal forms. Such building units are highly advantageous in the construction of a building wall in that they provide a wall of extremely simple and durable construction, one having dead air spaces which prevent the transmission of sound, moisture, heat and cold therethrough, and finally a wall which, by the employment of

spacing strips of various widths, can be varied in thickness while at the same time employing substantially the same amount of labor and materials.

5 Although I have herein shown and described only two forms of building walls embodying my invention and one form of building unit therefor, it is to be understood that various changes and modifications may 10 be made herein without departing from the spirit of the invention and the spirit and scope of the appended claims.

What I claim is:

1. A building wall comprising building 15 units arranged in spaced relation to each other, flanges extending inwardly from the confronting faces of the units, spacing strips interposed between the horizontal flanges of confronting units, and means for securing 20 the units in engagement with the spacing strips.

2. A building wall comprising, concrete building units arranged in rows, with the units of each row interlocked to each other 25 at their edges, separate means interposed between the rows for maintaining the units of one row in spaced relation to the units of the other row, and means for securing the rows of units against relative movement 30 with respect to the first means.

3. A building wall comprising building units arranged in rows in spaced relation with the confronting faces of the units in said rows so shaped at their upper ends 35 as to form opposing floor portions of a channel leaving an intervening space therebetween, and means extended across said intervening space to complete the floor of said channel.

40 4. A building wall comprising, building units arranged in double rows said rows being in spaced relation with the confronting sides of the units in said rows so shaped as to form at their upper ends opposing floor 45 portions of a channel adapted for the reception of concrete, and means for completing said floor and filling the interval between the upper ends of said units in the bottom of such channel, and spacing and alining 50 the row of units.

5. A building wall comprising, a concrete base, building units imbedded in the base at the lower ends and arranged in rows with the units of each row arranged edge to 55 edge and interlocked against relative lateral movement, flanges formed on the confronting faces of the units of each row, and spacing strips interposed between the flanges for determining the thickness of the wall, 60 and arranged to provide with the flanges a channel at the upper ends of the units and between the rows said channel filled with concrete, for the purpose described.

6. A building wall comprising, building units arranged in rows with the units of 65 each row contacting with each other and interlocked at their edges against lateral movement, flanges formed on the confronting faces of the units of the two rows in such manner to provide at the upper ends 70 of the units between the rows side portions of a concrete receiving channel, spacing and alining strips interposed between the rows of units and engaged by the flanges, rods extending through certain of the 75 flanges and projecting into said channel, and means engaged with said rods for connecting the units of one row with the corresponding units of the other row, said means being disposed within said channel. 80

7. A building wall comprising, building units arranged in rows with the units of each row contacting with each other and interlocked at their edges against lateral movement, flanges formed on the confronting faces of the units of the two rows in such manner to provide at the upper ends of the units between the rows portions of a concrete receiving channel, spacing and alining strips interposed between the rows of 90 units and engaged by the flanges, rods extending through certain of the flanges and projecting into said channel, and means for maintaining the building units in contact with the said strips comprising, a connecting rod arranged within the channel, and wires connected to said connecting rod and to the first rods. 95

8. A building unit for walls comprising a panel, tapered flanges extending laterally 100 from one side of the panel and so arranged as to provide at one end of the panel a terminal flange, and rods extending vertically through the flanges with their opposite ends projecting from the flanges. 105

9. A building unit for walls comprising a panel, flanges extending laterally from one face of the panel, and so arranged as to provide at one end of the panel a terminal flange, and rods extending vertically through 110 the flanges with an end projecting.

10. A building unit for walls comprising a panel, tapered flanges extending laterally from one face of the panel and so arranged 115 as to provide at one end of the panel a terminal flange, and rods extending vertically through certain of the flanges.

11. A building unit for walls comprising a panel, flanges extending laterally from one face of the panel and so arranged as to provide at one end of the panel a terminal flange, and rods extending vertically through 120 the flanges with their upper ends projecting from the flanges.

HENRY WARD HOWELL.
